Letters Patent No. 1826 - Dated Oct. 6th 1863.

Antedated July 4th 1863.

Design for Blind Binding.

mmmm

The schedule referred to in these Letters Patent and making part of the same.

To all whom it may concern:

Be it known that I, H. W. Kensing, of the City and County of Philadelphia, State of Pennsylvania, have invented or produced a new and original design for a Blind binding, and I do hereby declare the accompanying drawing, with the following explanation of the same, to form a full, clear and exact description of the said design.

The drawing represents sufficient of a strip of blind binding to illustrate my new design, which is composed of figures A and B, alternating throughout the length of the piece.

The form of the figure A, will be best understood by reference to the drawing, the figure B, being in the form of an oval, from each end of which project two diverging scrolls a, a, the whole surrounding a central lozenge shaped figure C.

I claim the ornamental figures and forms represented in and by the accompanying drawing, irrespective of the materials or colors used, and irrespective of the edging re-
